UNITED STATES PATENT OFFICE.

SAMUEL RAFFAPORT, OF BROOKLYN, NEW YORK.

BOX.

Application filed June 27, 1927. Serial No. 201,581.

My invention relates to a new and improved band-box.

One of the objects of my invention is to make a band-box of relatively fragile material such as thin paper which shall have superior durability.

Another object of my invention is to provide a relatively large band-box of the type used for packing millinery in which the 10 cover of the box is connected to the body portion of the box by an intermediate flexible strip which will permit the cover of the box to fall back until it can rest upon the support upon which the body of the box is 15 located.

Other objects of my invention will be set forth in the following description and drawings which illustrate a preferred embodiment thereof, it being understood that the 20 above general statement of the objects of my invention is intended to merely generally explain the same, and not to limit it in any manner.

Fig. 1 is a perspective view showing my 25 improved box.

Fig. 2 is a longitudinal central sectional view.

Fig. 3 is a plan view of the hinge.

The body portion 10 of the box is made 30 of thin flexible card-board which may be covered with any suitable flexible ornamental covering material and which preferably has a standard shape illustrated in Fig. 1, which shows a flat rear wall 12 and an outwardly bulging front portion. The cover 35 11 of the box has substantially the same contour as the body portion, and said cover 11 is made slightly larger than the body portion of the box so that the cover 11 can 40 be easily forced into the closing position and can be easily swung into the open position shown in Fig. 1. However, the cover 11 has a certain frictional fit with respect to 45 the body portion 10.

The cover 11 is connected to the body portion 10 by an intermediate strip 13 preferably made of card-board or other flexible material, this being scored along 50 the two hinge-like lines shown in Fig. 2, for example, to facilitate the bending of the said intermediate connecting strip 13. The first flange of the connecting strip 13 is connected to the flat rear wall of the box by means of fasteners 15 and the second 55 flange of the strip 13 is connected to the bulging front portion of the cover 11 by

means of ears 14 which are connected in any suitable manner to the bulging front portion of the cover. Hence, the second flange of the strip 13 forms the flat rear portion of the cover 11. This second flange is continuous with and in alignment with the remainder of the wall or flange of the cover. As shown in Fig. 2, wire fastening members 14' of the ordinary type may 60 be employed for connecting the ears 14 to the front or curved portion of the cover. 65

When the cover 11 is moved to the open position, then due to the flexibility provided by the double scoring of the member 70 13, the said cover 11 can fall back until it rests upon the double or other support upon which the box 10 is mounted. This prevents the breakage of the strip 13 because it is not compelled to support the 75 weight of the cover 11. It will be noted that in the position shown in Fig. 2 that the weight of the cover 11 imposes little or no strain upon the strip 13. The intermediate strip 13 differs from a hinge in that 80 the cover 11 can be moved longitudinally with respect to the body 10, when the cover has been raised from the body. Hence, to close the cover, it is turned until it contacts with the body, and the cover is then slid 85 forward until its depending wall can pass over the body.

I have described a preferred embodiment of my invention, but it is clear that numerous changes and omissions could be made 90 without departing from its spirit.

Claims:

1. A box having a body provided with a flat wall, a cover for said box having a contour corresponding to the contour of 95 said body, said cover having a wall adapted to fit over said body, and an intermediate rigid connecting strip having an intermediate portion connected to two end flanges which are bendable with respect to 100 said intermediate portion, one of said flanges being connected to the wall of said cover and constituting a flat wall portion thereof directly adjacent the flat wall of the body, said flat portion being continuous 105 with and in alignment with the remainder of the wall of the cover, the other of said flanges being connected to the flat wall of the body below the top thereof.

2. A box having a body provided with a 110 flat wall, a cover for said box having a contour corresponding to the contour of said

body, said cover having a wall adapted to fit over said body, and an intermediate rigid connecting strip having an intermediate portion connected to two end flanges which are bendable with respect to said intermediate portion, one of said flanges being connected to the wall of said cover and constituting a flat wall portion thereof directly adjacent the flat wall of the body, said flat portion being continuous with and in alignment with the remainder of the wall of the cover, the other of said flanges being connected to the flat wall of the body below the top thereof, said flanges being sufficiently bendable with respect to said intermediate portion to permit said cover to swing freely back until its free edge is at the level of the bottom of the body.

3. A box having a cardboard body pro-

vided with a flat wall, a cardboard cover 20 for said box having a contour corresponding to the contour of said body, said cover having a wall adapted to fit over said body, and an intermediate rigid cardboard connecting strip having an intermediate portion connected to two end flanges which are bendable with respect to said intermediate portion, one of said flanges having end 25 projections connected to the wall of the said cover, so that said flange constitutes a flat 30 wall portion of said cover directly adjacent the flat wall of the body, the other of said flanges being connected to the flat wall of the body below the top thereof, said flanges being freely bendable in both directions 35 with respect to said intermediate portion.

In testimony whereof I affix my signature.

SAMUEL RAPPAPORT.
